UNITED STATES PATENT OFFICE.

GEORGE ALBERT CHADDOCK, OF LIVERPOOL, ENGLAND.

DOOR OR WINDOW OR THE LIKE APERTURE-CLOSING DEVICE.

SPECIFICATION forming part of Letters Patent No. 745,783, dated December 1, 1903.

Application filed September 8, 1902. Serial No. 122,565. (No model.)

To all whom it may concern:

Be it known that I, GEORGE ALBERT CHADDOCK, master mariner, a subject of the King of Great Britain, residing at Knotty Ash, Liverpool, in the county of Lancaster, England, (whose full postal address is 56 Thomas Lane, Knotty Ash aforesaid,) have invented certain new and useful Improvements in Doors, Windows, or the Like Aperture-Closing Devices, (for which application has been made in Great Britain, No. 3,403, dated February 11, 1902,) of which the following is a specification.

This invention relates to improvements in doors, windows, and the like aperture-closing devices, and has for its object to provide a door or the like which can be easily opened and closed and which when closed can be held tight against weather or the passage of water, fire, or air or thieves. In the case of bulkhead-doors of ships or the doors and windows of large land buildings or structures where a number of such closing devices are employed the closing and opening of any or all can by this invention be effected either simultaneously from a central control or independently by local operation or control.

The invention also provides for a space being temporarily left for the circulation of air or escape of people from the room or other place closed by the door, window, or the like when the main portion of the aperture has been closed and before the final closing of the whole.

The invention will be described with reference to the accompanying drawings, in which—

Figure 1 is a front elevation, partly in section, of a door, window, or the like constructed in accordance with my invention. Fig. 2 is an end view, partly in section. Fig. 2^a is a detail showing the main shaft for operating several doors, windows, or the like simultaneously. Fig. 3 is a transverse section on the line *x* *x* of Fig. 1. Fig. 4 is an enlarged detail view of the upper part of Fig. 2, showing the sleeve *H* in section. Fig. 5 is an enlarged perspective view of the plate *J* and sleeve *H*. Fig. 6 is an enlarged detail of the locking device. Fig. 7 is an enlarged cross-section of the casing *G*, showing the groove *g*, with the shutter and window removed.

According to my invention I construct a door, window, or the like *A* of any suitable or desired shape, but of less height than the aperture to be closed, leaving a space *B* at the top, which according to the purpose in view is made either small, as for ventilating purposes, or large to allow of a person climbing over and escaping. I mount the door, window, or the like so as to rotate on a central axis—for instance, on a central shaft *C*—and provide a sliding shutter *D*, adapted to be brought down to close the upper space *B* after the door or window has been turned and closed.

The meeting edges of the bottom of the door, window, or the like and the sill or bottom of the doorway or other aperture to be closed are made to fit the one into a groove in the other, and the door, window, or the like is made vertically movable to some extent in addition to its movement of rotation in order to allow it to be lifted to bring it clear of the sill for the turning movement. In this way an efficient tight joint can be obtained for the purposes before indicated. In a similar manner the meeting edges of the shutter *D* and top of the door, window, or the like *A* are made to effect a tight joint, and the sliding shutter *D* in being brought down by suitable mechanism onto the door, window, or the like to close the top space *B* is utilized also to press together the meeting edges at the bottom of the door, and thus bind all together in a thoroughly tight manner.

Fig. 2 shows one method of jointing the meeting edges, the top of the door or the like having a *V* or half-round section to fit into a groove *d* in the shutter *D* and the bottom of the door being adapted to fit into a groove *e* in the sill *E*. The shutter *D* in the form shown in the drawings is made to slide within a recess *f* in the top frame of the window or door, Fig. 2, and its ends slide in grooves *g* in the side frames *G*, Figs. 1 and 7. The sides of the door, window, or the like *A* are made to overlap or joint in a tight manner—as shown, for example, in Fig. 3—without interfering with the movement of rotation of the door or the like on its central axis *C*.

Various forms of mechanism may be utilized for obtaining the vertical and rotary movements of the door *A* and the vertical

movement of the shutter D. The mechanism shown in the drawings for such purposes consists as follows: The central shaft C is threaded at its upper end to engage in a nut 5 or internally-threaded sleeve H, secured firmly to the shutter D—for instance, as shown in Fig. 4, by means of a plate J, screwed or otherwise attached to the shutter D and having a central boss j bored to drop 10 over the sleeve H and secured by a lock nut or plate K, screwed onto the sleeve H, which is threaded at its upper portion—such threaded portion of the sleeve being formed with one or more flat sides H', as shown in Fig. 15 5, to fit a corresponding flat inside the boss j to prevent the sleeve from turning in the shutter D. By rotating the shaft C, which is provided, for instance, with bevel-gear L l, which may be operated by a hand-wheel 20 M, the nut or sleeve H, and therewith the shutter D, may be moved up or down to open or close the space B. On the nut or sleeve H is formed a flange or shoulder h, on which the door, window, or the like A is rev- 25 olubly suspended in the open position of the shutter, Fig. 1—for instance, by means of the cover-plate N, screwed to the window and having a central hole in which the nut or sleeve H may freely slide. The plate N is 30 turned down over the back and front of the window, as shown in Fig. 4, to cover the space within which the flange h plays. It will be seen that the connection of the nut or internally-threaded sleeve H to the shutter D by 35 means of the removable plate J and lock nut or plate K enables the cover-plate N to be slipped onto the sleeve H with facility in the course of construction, thereby enabling the flange or shoulder h to be constructed inte- 40 gral with the sleeve for the purpose of strength.

The door, window, or the like, revolvably hung, for instance, by the cover-plate N on the flange h by its upper end in the manner before described, has also its lower end guided 45 by a plate O, secured by screws to the bottom of the door or the like and having a hole through which the central shaft C freely passes. This plate O is formed or provided with a clutch P or like device adapted to grip 50 a similar clutch or device P', fixed rigidly on the shaft C somewhat above the clutch P. On the shaft C being rotated (for instance, clockwise) to open the door or window the nut or sleeve H first rises, taking with it the shutter D and opening the space B, as shown 55 in Fig. 1. When the space B is almost fully open, the flange h engages the cover-plate N, Fig. 1, and on further rotation of the shaft the shutter D in rising further at once com- 60 mences to lift vertically the door, window, or the like A, thus bringing the bottom edge of the latter out of the groove e of the sill or casing E. During this movement the clutch P, carried by the window, gradually approaches 65 its related clutch P' of the shaft until at the moment when the bottom of the door A is clear of the sill or casing E the two clutches

are engaged, and the further rotation of the shaft C now carries with it the door, window, or the like A, which can thus be swung fully 70 or partly open on its central axis, according as desired. To close the structure, the motion of the shaft C is reversed, (for instance, anticlockwise,) thus first rotating the door or window A into the closed position, at which moment, 75 however, the swinging of the door A is of course terminated, and the continued rotation of the shaft causes the nut or sleeve H to travel down the shaft, thus lowering the still suspended door, window, or the like A somewhat into 80 the groove e. At the same time the clutch P drops out of engagement with the clutch P'. In this position the door, window, or the like may be allowed to remain, leaving the upper space B open for the purposes of ventilation 85 or for the escape of persons by climbing over, in which case the space B is made of sufficient dimensions for that purpose. The further rotation of the shaft C in the same direction brings the shutter D down onto the top 90 of the door, window, or the like, thus closing the space B, and enables sufficient pressure to be brought to bear to bind all in a thoroughly tight manner.

In order to facilitate the engaging and release of the clutch members P P', the member P, which is carried by the door or window A, is loosely mounted on a boss Q of the plate O and has a pin engaging in a helical slot q at each side in said boss. (See Fig. 2.) The 100 moment the clutch P commences to engage the member P' it makes a partial rotation on the boss Q, and by means of its pins riding up helical slot q in the latter it is lifted into close engagement with the clutch P', thus obviating any slipping of the clutch-teeth. The door or window is thus not turned until the clutches are fully engaged—i.e., when the pins have reached the upper end of the slots q. This lifting action may be assisted by forming inclined faces or notches r, Figs. 1 and 2, on the flange h of the nut or sleeve H and providing projections s, Fig. 1, on the cover-plate N of the door or window to ride on the inclined faces or notches r, so as to give a 115 slight lift to the door or window (and therewith the clutch P) when the door is turned in its opening movement.

The operation of the actuating-shaft C in the manner described will usually be carried 120 out by hand independently for each window, door, or the like by means of a hand-wheel M, as before stated. A suitable locking device may be provided for locking the door or the like in any position into which it may 125 have been placed. A convenient means is shown in Figs. 2 and 6, in which the hand-wheel M rotates in front of a stationary disk T and a series of grooves or half-holes u' is formed round the periphery in the inner 130 face of the wheel M and a single groove or half-hole u² in the opposing face of the disk T, as shown in Fig. 6, a pin u being provided which is too large to drop into a half-hole

until one of these is brought opposite the single groove, according to the position taken by the hand-wheel in adjusting the window, whereupon the parts are locked. In the case 5 of bulkhead-doors of ships or the doors or windows of large land buildings where a number of closing devices are required to be opened or closed simultaneously from a central control the hand-wheel M is replaced by 10 a bevel-wheel gearing with a related bevel-wheel on a main shaft Z, as shown in Fig. 2^a. In this way any number of doors or windows may be geared to and actuated by said main shaft.

15 It will be seen that by the present invention the top and bottom of the door, window, or the like is made thoroughly tight when closed. The sides may similarly be rendered tight under the binding pressure of the shutter D by providing the sides of the door or the like A with several oblique slots or grooves x, as shown in Fig. 2, and providing pins y on the casing or frame G of the door, window, or the like to engage in said slots or 25 grooves when the door is almost fully closed, whereby the downward movement of the door under the pressure of the shutter D in the final closing of the door produces a wedging action which draws the door, window, or the 30 like closely up against its casing or frame and makes a thoroughly tight joint at the sides, whereby the tight closure is complete all round.

I declare that what I claim is—

35 1. In a door, window, or like aperture-closing device, the combination of an aperture-casing, a closing member revolubly mounted therein on a vertical axis with vertical play thereon, said closing member being of lesser 40 height than the aperture, means for rotating said member to open and close the main portion of the aperture, a shutter mounted with vertical play at the head of the aperture, means for vertically moving said shutter to 45 open or close the space remaining at the top, and connections on the shutter and the closing member adapted to engage when the shutter has been lifted to open the top space, whereby a further lifting and return of the 50 shutter moves the closing member vertically in its closed position of swing to open and make a tight joint with the casing at the bottom, substantially as described.

2. In a door, window, or like aperture-closing device, the combination of an aperture-casing, a closing member revolubly mounted therein on a vertical axis with vertical play thereon, said closing member being of lesser height than the aperture, means for rotating 55 said member to open and close the main portion of the aperture, the sides of the closing member and of the casing having a form adapted to fit one to the other in a tight-closing manner in the closed position, a shutter mounted with vertical play at the head of the aperture, an internally-threaded sleeve secured to said shutter, a threaded shaft within

60 said sleeve adapted to be rotated to vertically move said sleeve and shutter to open and close the top space, and a flange or shoulder on the bottom of the sleeve adapted to engage and revolubly suspend the closing member when the shutter has been lifted to open the top space, whereby a further lifting and return of the shutter moves the closing member vertically in its closed position of swing to open and make a tight joint at the bottom, substantially as described.

3. In a door, window, or like aperture-closing device, the combination of an aperture-casing, a vertical shaft revolubly mounted in said casing, a closing member mounted revolubly and vertically movable on said shaft within the aperture, means for rotating said shaft, clutch mechanism on said shaft adapted to be operated by said shaft to rotate the closing member and open and close the aperture, and means adapted to be actuated by said shaft to move said member vertically in the closed position to make or open a tight joint with the casing at the bottom, substantially as described.

4. In a door, window, or like aperture-closing device, the combination of an aperture-casing, a vertical shaft revolubly mounted in 9: said casing, a closing member mounted revolubly and vertically movable on said shaft within the aperture, said closing member being of lesser height than the aperture, means for rotating said shaft, clutch mechanism on 10: said shaft and member adapted to be operated by said shaft to rotate the closing member and open and close the main portion of the aperture, means adapted to be actuated by said shaft to move said member vertically in the closed position to make or open a tight joint with the casing at the bottom, a shutter mounted with vertical play at the head of the aperture, and means adapted to be actuated by said shaft to vertically move said shutter 11: and open or close the space remaining at the top, substantially as described.

5. In a door, window, or like aperture-closing device, the combination of an aperture-casing, a vertical shaft revolubly mounted in 115 said casing, a closing member mounted revolubly and vertically movable about said shaft within the aperture, said closing member being of lesser height than the aperture, means for rotating said shaft, clutch mechanism on 120 said shaft and member adapted to be operated by said shaft to rotate the closing member and open and close the main portion of the aperture, a shutter mounted with vertical play at the head of the aperture, a screw-thread on 125 the upper end of the shaft engaging a corresponding internal thread through the shutter and adapted to vertically move said shutter to open or close the space remaining at the top of the aperture, and means on said shutter to raise or lower said member in a closed position to make or open a joint with the casing at the bottom, said shutter being adapted to press on the upper edge of the door to ren-

4
der the joints at top and bottom thoroughly tight, substantially as described.

6. In a door, window, or like aperture-closing device, the combination with a closing member revolubly mounted in the aperture on a vertical axis with vertical play thereon; of a shaft C, clutch member P' on said shaft, clutch member P mounted on the closing member with limited vertical helical play thereon, and means adapted to be actuated by said shaft to vertically move the closing member and therewith the clutch member P to engage or release the clutch members, substantially as described.

7. In a door, window, or like aperture-closing device, the combination with a closing member revolubly mounted in the aperture on a vertical axis with vertical play thereon; of a shaft C, clutch member P' on said shaft, clutch member P mounted on the closing member with limited vertical helical play thereon, a screw-thread on the upper end of said shaft, a nut or internally-threaded sleeve H on said threaded end of the shaft, a shutter mounted with vertical play at the head of the aperture, the closing member being of lesser height than the aperture and the shutter being adapted to open and close the space remaining vacant at the top, means for attaching said shutter to said nut or sleeve H, and means on said sleeve adapted to vertically move the closing member and therewith the clutch member P to engage or release the clutch members and make or open a tight joint at the bottom, substantially as described.

8. In a door, window, or like aperture-closing device, the combination of shaft C, nut or sleeve H on the threaded end thereof, flange h having inclines or notches r, plate N having projections s, clutch member P' and

plate O carrying a clutch member P, substantially as described.

9. In a door, window, or like aperture-closing device, the combination of an aperture-casing, a closing member revolubly mounted therein on a vertical axis with vertical play thereon, means for rotating said member to open and close the aperture, means for moving said member vertically in the closed position to make or open a tight joint with the bottom, and devices at the sides of the member and its casing comprising pins and inclined guides adapted to coact in the downward movement of the member to draw the member against the casing on all sides, substantially as described.

10. In a door, window, or like aperture-closing device, the combination of an aperture-casing, a vertical shaft revolubly mounted in said casing, a closing member mounted revolubly and vertically movable on said shaft within the aperture, means for rotating said shaft, clutch mechanism on said shaft adapted to be operated by said shaft to rotate the closing member and open and close the aperture, means adapted to be actuated by said shaft to move said member vertically in the closed position to make or open a tight joint with the casing at the bottom, and a system of shafting with gearing adapted to enable said vertical shaft to be operated thereby simultaneously with the related shafts of other apertures all from a central control, substantially as described.

In witness whereof I have hereunto signed my name, this 30th day of August, 1902, in the presence of two subscribing witnesses.

GEORGE ALBERT CHADDOCK.
